APPARATUS FOR PREFABRICATING COVING
Charles A. Schweitzer, deceased, late of Almont, Mich.,
by Gertrude M. Schweitzer, executrix, 194 W. Stone St.,
Almont, Mich.

Filed June 12, 1958, Ser. No. 741,673
8 Claims. (Cl. 156—588)

This invention relates to novel prefabricated coving structure and to special apparatus and process for forming the same.

In practicing the invention the coving is made by selecting strips of hardboard, plasterboard or the like, which will be referred to generically herein as hardboard, of the type usually used for drywall construction in modern housing.

It is the major object of the invention to provide a novel prefabricated hardboard coving.

A further object is to provide a novel preformed laminated coving structure.

It is another object of the invention to provide novel apparatus and process for the manufacture of prefabricated coving.

A further object is to provide a novel apparatus and process for making prefabricated coving wherein laminated strips of hardboard surface bonded with incurred adhesive are preformed in progressive steps to a final form where the adhesive is cured.

It is a further object of the invention to provide a novel apparatus and method for making prefabricated coving wherein laminated hardboard is subjected to successive independent forming operations and held in final form until it achieves a permanent set.

Further objects of the invention will appear as the description proceeds in connection with the appended claims and the annexed drawings wherein:

FIGURE 1 is an end elevation of the novel coving strip of the invention;

FIGURE 2 is a perspective view of a length of coving;

FIGURE 3 is a side elevation partly in section showing apparatus according to a preferred embodiment of the invention and showing a glued strip in position to be formed;

FIGURE 4 is a fragmentary view in section showing the first forming step wherein the holder bar is lowered to clamp the inner edge of the strip;

FIGURE 5 is a similar fragmentary view showing the second forming step wherein the intermediate bar has been lowered upon the strip and imparted the first bend thereto;

FIGURE 6 is a further fragmentary view showing the third forming step wherein the main bar has descended into contact with the strip to impart its final curvature; and

FIGURE 7 is a fragmentary front elevation showing the apparatus in further detail.

The novel coving strip of the invention, which may be made in any desired length, is shown best in FIGURES 1 and 2 and comprises a laminated structure consisting essentially of a front strip 11 and a thicker back strip 12 formed to a desired curvature with an interface 13 of adhesive between them. Strips 11 and 12 are of the same width and length and are preferably lengths of so-called hard board which is a synthetic board made of compressed cellulosic fibres. This hard board is available under many different trade names and it comprises stiff slabs or strips of compressed fibrous material which may be sawed like wood and which may be preformed to a given curve as in practicing the invention. For example, the thicker strip 12 may be made of Upson white board and the thinner strip 11 of Upson all weather

2

board, and equivalent materials of other manufacture are available.

It has been found in practicing the invention that the front concave surface 14 of coving made according to the invention is smooth and free of wrinkles as a result of the special novel process of making it hereinafter described.

When installed the coving is usually mounted in the corner formed by two intersecting room walls as at 15, 16 and a straight wooden heel strip 17 is adhesively secured all along the back of the formed strip near one edge. This strip 17 is essentially of wedge shape with a surface 18 to lie flat on the adjacent wall, and a series of screw fasteners 19 along the strip attach it to the wall. The back of other edge of the strip bears flexibly against the wall 16 when screws 19 are tight, and the tops of screws 19 may be countersunk and filled with putty and painted over so that a smooth clean surface 14 appears at the room corners.

20 The forming apparatus comprises a suitable rigid support 21 upon which is mounted an arcuate fixed die member 22 having a smooth front surface 23 conforming to the desired curvature of surface 14 of the coving. Preferably die member 22 is of sheet metal and its surface 23 is polished. Heaters 24 are mounted so as to be housed by the die member and are distributed to substantially uniformly heat surface 23 to a desired adhesive curing temperature as will appear. The foregoing provides a longitudinally straight heated fixed lower die surface.

25 The movable die members consist essentially of intermediate bar 25 and main bar 26 which are mounted on the support above the fixed lower die member and adapted for independent movement toward the fixed die member.

30 The forming surface 27 of bar 25 has the same curvature as the adjacent steeper curved portion of fixed die surface 23, and the forming surface 28 of die bar 26 has the same curvature as the remainder of fixed die surface 23, and when both the intermediate and main bars are lowered to clamp a coving strip against surface 23, the surfaces 27 and 28 are essentially continuations of each other. All elements of surfaces 23, 27 and 28 are parallel and perpendicular to the plane of the paper, and these surfaces are coextensive in length.

35 Intermediate bar 25 is a composite structure comprising a main portion 29 that has a smooth guide face 31 adapted to slide along the smooth flat fixed guide surface 32 of a strip 33 on the support. At its inner corner the main portion 29 has a recess 34 in which is disposed a holder bar 35. The forming surface 36 of bar 35 is an effective continuation of surface 27 during the operation as will appear.

40 A series of pockets 33 are formed in main member 29 opening into recess 34 to accommodate coil springs 39, and stems 41 extend freely through bores 42 to terminate in enlarged heads 43. When the parts are as in FIGURE 3, the compression springs project holder bar 35 a short distance below the surface 27, the amount of such projection being limited by heads 43.

45 A sturdy fixed guide block 44 extends the length of the support and it is formed with a plurality of bores 45 slidably supporting a plurality of links 46 connected at their lower ends to the main portion 29 of intermediate die bar 25. The upper ends of links 46 are connected pivotally at 47 to the ends of short crank arms 48 all fixed on a longitudinal shaft 49 suitably rotatably mounted on the support. Rocking of shaft 49 is controlled as by a crank 51 pivotally connected to a foot treadle operated arm 52.

50 Compressed between the main body portion 29 of die bar 25 and the fixed support block 44 are a series of

powerful coiled compression springs 53. In FIGURE 3 these springs 53 are shown under maximum compression, this being accomplished by the upward pull of links 46 upon clockwise rocking of cranks 48 and shaft 49. A suitable latch on arm 52 maintains the parts in the FIGURE 3 position. When shaft 49 and cranks 48 are rocked counterclockwise, as by release of the latched arm 52, the springs 53 all expand together to force the intermediate die bar 25 toward the fixed die member.

The main die member 26 is mounted for movement 10 parallel to die member 25 and is fixed to the lower ends of a series of bars 54 slide guided at 55, 56 on the support 21 and formed with rack teeth 57 meshed with pinions 58 on a shaft 59 rotatably mounted on support 21 and provided with a handwheel 61.

In practicing the process of the invention two flat strips of hardboard are selected of desired size. The strips are of the same length and width but are preferably of different thickness, with the inner strip 11 being thinner. For example, for the usual housing construction strips of hardboard 11 and 12 are selected that are about twelve inches wide and some standard length such as fifteen feet. The strip 11 may be about one-eighth inch thick and strip 12 may be about three-sixteenths inch thick.

The strips are first coated over their entire interface 25 area 13 with a suitable liquid adhesive and placed in full surface area contact. The glue adhesive may be of any suitable type which does not set or dry too quickly because it is important in the process that the adhesive not be set during the forming operations.

The flat adhesive bonded assembly is now ready to be introduced into the press apparatus for forming and it is pushed in edgewise as shown in FIGURE 3 until the longitudinal edge 70 abuts the flat smooth stop face 71 that extends along support 21. The intermediate and main die bars are in raised position at this time as shown in FIGURE 3.

Now the treadle bar 52 is unlatched and the intermediate die bar 25 descends mainly under the influence of 40 springs 53. This descent may be aided or at least started by a positive rocking of shaft 49 by the treadle bar to exert a downward push on die 25.

First, the extended holding bar 35 contacts the laminated hardboard assembly all along its inner edge over a width of about an inch or two. This clamps the laminated hardboard strip edge tightly against the underlying fixed die surface 23 and prevents any outward movement of the strip away from stop face 71 during subsequent forming. This is shown in FIGURE 4.

Die member 25 continues to descend under the pressure of springs 53 until forming face 27 contacts and bends the hardboard assembly over the adjacent surface 23. During this action the entire holding bar 35 is displaced into recess 34, because the total force of springs 53 is much less than that of springs 53. Finally the parts reach the position shown in FIGURE 5 wherein holding bar 35 becomes essentially part of the intermediate die and surfaces 27 and 36 are substantial continuations of each other.

Now the forming of the steeper curved portion of the coving is complete and about a third of the coving is tightly clamped in the press. The springs 53 exert this heavy clamping pressure and this arrangement permits the forming of a wide range of thicknesses of material without resorting to adjustments.

The operator now turns handwheel 61 to rotate shaft 53 and pinions 59 so that the rack bars 54 are simultaneously displaced to move main bar 26 down until forming surface 28 engages and bends the laminated hardboard assembly to conform to the fixed curvature of surface 23 as shown in FIGURE 6.

During the forming operations wherein surfaces 27 and 28 are engaging the upper surface of the laminated strip, some slight relative sliding movement occurs between the strips 11 and 12 outwardly of the clamped edge as per-

5 mitted, and even aided, by the still wet glue interface which acts as a lubricant, so that after the apparatus parts assume the position shown in FIGURE 6 the thinner strip 11 extends past the outer edge of strip 12 a small distance, say about a quarter of an inch. This occurs since the inner edge is tightly clamped by the holding bar.

After the parts assume the position of FIGURE 6, the intermediate and main die members are maintained in position for a sufficient length of time to allow the glue adhesive to set and permanently bond strips 11 and 12 together in the formed condition. This setting or curing of the adhesive is speeded and promoted by heaters 24 which impart the necessary temperature to die surface 23.

When the adhesive has been set the press is released 15 by raising the intermediate and main dies to the open position of FIGURE 3 and the formed coving removed. Then heel strip 17 may be adhesively attached in another strip, if needed, and the edge where the strips overlap is trimmed back to remove the overlap. The coving is now 20 ready to use and may be cut to desired length.

A curved coving strip formed in accord with the foregoing has a smoothly curved non-wrinkled concave face 14, and this is attributed mainly to the provision for relative sliding of the strips 11 and 12 during forming. By using the thinner more flexible inner strip 11 the tendency to wrinkle is even further reduced.

30 The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. Apparatus for prefabricating coving comprising a support, means defining an edge positioning surface on said support, a fixed die member on said support having a continuous surface extending away from said edge positioning surface and conforming to the desired coving shape, an intermediate die member movably mounted on said support for displacement toward and from said fixed die surface and having a forming surface corresponding to one part of said fixed die surface, a holding member resiliently and movably mounted on said intermediate die member adjacent said edge positioning surface, and a main die member movably mounted on said support independently of said intermediate die member for displacement toward and from said fixed die surface and having a forming surface corresponding to another part of said fixed die surface, and means for independently moving said movable die members toward said fixed die member, said holding member being so mounted on said intermediate member that upon movement of said intermediate member toward said fixed die member the holding member will engage and clamp the edge of a coving strip held against said positioning surface before said coving strip is engaged by said intermediate member.

2. Apparatus for prefabricating coving comprising a support, means defining an edge positioning surface on said support, a fixed die member on said support having a continuous surface extending away from said edge positioning surface and conforming to the desired coving shape, an intermediate die member slidably mounted on said support for displacement toward and from said fixed die surface and having a forming surface corresponding to one part of said fixed die surface, a holding member slidably and resiliently mounted on said intermediate die member adjacent said edge positioning surface, and a main die member slidably mounted on said support independently of said intermediate die member for displacement toward and from said fixed die surface and

having a forming surface corresponding to another part of said fixed die surface, and means for independently moving said movable die members toward said fixed die member, said resilient mounting for said holding member urging said holding member toward said fixed die member in advance of the intermediate die member so that when said intermediate die member is moved toward the fixed die member the holding member will engage and clamp the edge of a coving strip held against said positioning surface before said coving strip is engaged by said intermediate die member.

3. In the apparatus defined in claim 2, resilient means stronger than the resilient mounting of said holding member and compressed by separational movement of the intermediate die member from the fixed die member adapted for urging said intermediate die member toward said fixed die member with sufficient coving strip forming pressure.

4. In the apparatus defined in claim 3, cooperating rack and pinion means on the support and fixed die member for moving said main die member with respect to said fixed die member.

5. Apparatus for prefabricating coving comprising a support, means defining an edge positioning surface on said support, a fixed die member on said support having a surface extending away from said edge positioning surface and conforming to the desired coving shape, an intermediate die member movably mounted on said support for displacement toward and from said fixed die surface and having a forming surface corresponding to one part of said fixed die surface, a holding member movably mounted on said intermediate die member adjacent said edge positioning surface, and a main die member movably mounted on said support for displacement toward and from said fixed die surface and having a forming surface corresponding to another part of said fixed die surface, and means for independently moving said movable die members toward said fixed die member said holding member being resiliently mounted in a recess in said intermediate die member and adapted to be withdrawn into said recess when said intermediate die member has been moved to engage a coving strip to be formed between said surfaces.

6. Apparatus for prefabricating coving comprising a support, means defining an edge positioning surface on said support, a fixed die member on said support having a surface extending away from said edge positioning surface and conforming to the desired coving shape, an intermediate die member movably mounted on said support for displacement toward and from said fixed die surface and having a forming surface corresponding to one part of said fixed die surface, a holding member movably mounted on said intermediate die member adjacent said edge positioning surface, and a main die member movably mounted on said support for displacement toward and from said fixed die surface and having a forming surface corresponding to another part of said fixed die surface, and means for independently moving said movable die members toward said fixed die member, said holding member being resiliently mounted in a recess in said intermediate die member and adapted to be withdrawn into said recess when said intermediate die member has been moved to engage a coving strip to be formed between said surfaces, and said holding member comprising a bar having a surface that is a substantial

continuation of the surface of said intermediate die member in said withdrawn condition.

7. Apparatus for prefabricating coving comprising a support, means defining an edge positioning surface on said support, a fixed die member on said support having a surface extending away from said edge positioning surface and conforming to the desired coving shape, an intermediate die member movably mounted on said support for displacement toward and from said fixed die surface and having a forming surface corresponding to one part of said fixed die surface, a holding member movably mounted on said intermediate die member adjacent said edge positioning surface, and a main die member movably mounted on said support for displacement toward and from said fixed die surface and having a forming surface corresponding to another part of said fixed die surface, means for independently moving said movable die members toward said fixed die member, and resilient means reacting between said intermediate die member and the support and compressed by separation of the intermediate die member from the fixed die member for urging said intermediate die member toward said fixed die member.

8. Apparatus for prefabricating coving comprising a support, means defining an edge positioning surface on said support, a fixed die member on said support having a surface extending away from said edge positioning surface and conforming to the desired coving shape, an intermediate die member movably mounted on said support for displacement toward and from said fixed die surface and having a forming surface corresponding to one part of said fixed die surface, a holding member movably mounted on said intermediate die member adjacent said edge positioning surface, and a main die member movably mounted on said support for displacement toward and from said fixed die surface and having a forming surface corresponding to another part of said fixed die surface, means for independently moving said movable die members toward said fixed die member, said holding member being resiliently mounted in a recess in said intermediate die member and adapted to be withdrawn into said recess when said intermediate die member has been moved to engage a coving strip to be formed between said surfaces, and resilient means cooperating with said intermediate member of sufficient strength to exert a coving forming pressure so positioned relative to said intermediate die member and said holding member as to transmit a coving holding pressure through said intermediate die member to said holding member.
